UNITED STATES PATENT OFFICE.

JAMES ALWARD SEYMOUR, OF AUBURN, NEW YORK.

VALVE-GEAR.

SPECIFICATION forming part of Letters Patent No. 628,121, dated July 4, 1899.

Application filed February 27, 1897. Renewed May 25, 1899. Serial No. 718,194. (No model.)

To all whom it may concern:

Be it known that I, JAMES ALWARD SEYMOUR, of the city of Auburn, State of New York, have invented certain new and useful 5 Improvements in Valve-Gear for Steam-Engines, of which the following is a description, reference being had to the accompanying drawing, forming part of this specification.

My invention relates to the valves and operating mechanism by which the admission and cut-off of steam to the cylinders of steam-engines are controlled; and it consists in certain novel arrangements and combinations of the valve-actuating mechanisms whereby the 15 regular movement imparted to the valves by their actuating devices is, by means of connecting devices interposed between said actuating devices and said valves, made irregular, and the speed of said valves varies at different points of their travel, being quickened 20 at times and then retarded, so that the valves are made to pause at one end of their stroke and a dwell or diminution of speed occurs.

The object of the variation of the speed or 25 movement above referred to is to diminish the travel of the valves after they are closed, or, in other words, to give the valves such travel as shall be necessary to secure adequate port-opening and a sufficient seal when 30 closed, and to suppress, further, unnecessary valve motion, which usually takes place after closing of the valve and when an unbalanced valve is under considerable steam-pressure, producing proportionate friction.

35 It will be evident that the pause above referred to may be accomplished by various forms of connecting mechanisms. In fact, any form of connecting mechanism in which a member to which is imparted a rocking or 40 pendulum motion serves to actuate a succeeding member having a rocking or reciprocating sliding movement interposed between the valve and its actuating-eccentric will accomplish this result if properly positioned and 45 timed relative to one another.

The drawing forming part of this specification is intended simply to illustrate one form of mechanism by which the above-described function may be accomplished.

50 The pause above described is of particular value as applied to multiported or gridiron

valves, because in such valves, each grid being functionally a separate valve, if the eccentric motion be unvaried and be transmitted directly to the valve without the intervention of some accelerating or retarding mechanism the valve travel will be so much increased that in order to prevent each grid from interfering with the functions of its adjacent grid it would be necessary to space them so far apart as to cause a great length 55 of valve, which, with the requisite corresponding length of steam-chest and port, would involve an inconvenient, if not an impracticable, construction and result in an undesirable 60 waste of steam from the necessarily large clearance-space. These difficulties have heretofore been avoided by the use of a releasing type of valve-gear with a single valve for both admission and cut-off of steam instead of the 65 preferable positively-driven type of valve.

It is intended hereby to limit the scope of this invention to the combination, with multiported or gridiron valves situated at each end, respectively, of the cylinder, each being actuated by a fixed eccentric, which valves effect the admission of steam to the cylinder at the proper time, of similar multiported or gridiron valves superimposed thereupon and serving as cut-off valves, being actuated by 75 an eccentric, the position of which with reference to the crank is variable and under control of the governor and the interposed valve-controlling and speed-varying mechanism, which produce the dwell or diminution of 80 speed at certain points of the travel of both said main and cut-off valves, as hereinbefore described. As the valve-gear which forms the subject-matter of the present invention 85 is well adapted for use in connection with the type of valve shown, it is capable of use with other forms of steam-valves.

Referring to the drawing, a rocking-shaft G, moving with regular rocking or oscillating motion imparted by an eccentric or crank, is 95 provided with the rocker-arm H, connecting through pin A and link I to a pin A', passing through the radius-bar J and link U, the latter operating through pin Y upon the slide K, attached to the main valve M by the valve-rod L. The regular movement due to the eccentric of the rock-shaft G above men-

tioned is represented by the extreme positions of the center of the pin A—viz., *a* and *c*—and the center of this travel is represented by the point *b*. The corresponding positions 5 of the center of pin A' are represented by points *a'* *b'* *c'*, corresponding to points *a* *b* *c*, respectively, above mentioned. It will be noted that both *a* and *c* are equally distant from *b*, but that *b'* is situated nearer to *c'* 10 than to *a'*. The irregular motion communicated to the valve M through link U, slide K, and rod L is still further increased, so that *a''* *b''* *c''* represent various positions of a single point on the valve M and correspond to 15 positions *a* *b* *c* above mentioned, position *b''* being very much nearer to *c''* than to *a''*.

It will be noted that the irregularity or change of the movement of the valve M is accomplished by two stages, which enables a 20 longer pause motion or diminution of movement to be effected at end of stroke of valve, but which is not essential to securing substantially the advantages of the invention which can be secured by a single-stage distortion. In a similar manner the rock-shaft 25 N receives a regular rocking movement from the governor-eccentric. The travel of the center of the pin D in rocker-arm V, situated upon this rock-shaft N, is represented by the line *d e f*, the extreme points of travel being represented by *d* and *f* and the center point by *e*, this motion being communicated through the link O and pin D' to the bell-crank P, pivoted at Q. The positions of the centers 30 of the pin D', connecting said link O and bell-crank P, will be represented by *d' e' f'*, corresponding to movement *d e f* above mentioned, the motion being from this point transmitted without further variation through bell-crank 35 P, the pin D'', the link R, the pin X, and the valve-rod S to the cut-off valve T, the positions of a single point upon the latter corresponding to *d e f* being *d''' e''' f'''*, the point *e'''* being nearer to *f'''* than to *d'''*, whereas 40 in the original motion *d e f*, *e* is equally distant from *d* and *f*.

It will be noted in the drawing that the irregularity is carried to such an extent that *c'* moves past the position at which center 45 lines of the toggle-joint mechanism formed by the radius-link J and link U are in a straight line. This causes a slight return movement of the valve at one end of the stroke, after which it returns to the extreme 50 position *w* before making the main stroke, so that the point *c''* although corresponding to the extreme point of travel of the eccentric is not at the extreme position of the valve. *c''*, in fact, is farther from it than the point *b''* 55 and falls between *b''* and *a''*. It will be apparent that by thus forcing the said toggle-joint past its center the length of the dwell of the valve is materially increased, although the state of actual rest of the valve is but 60 momentary, as it is making its forward and return movement due to the toggle-joint passing its center before it starts on its re-

turn port-opening stroke, so that all danger of the valve sticking by reason of remaining too long at rest is removed.

7c

It should be observed that it is not necessary to vary and change the motion of the eccentric sufficiently to fully obtain the conditions above described, since very substantial benefits will accrue when only a slight 75 variation in the motion of said eccentric occurs.

From the foregoing it will be seen that the valves reach their maximum rapidity of movement during the first part of the stroke of the 80 rocker-arms on the rock-shafts and that the dwell or diminution of speed occurs during the latter half of said stroke, or when the valve is at the end of its travel, so that unnecessary movement of the valve is done 85 away with.

Having thus described my invention, what I claim as new, and desire to secure by Letters Patent, is—

1. The combination with a multiported or 90 gridiron main valve for each end of the cylinder, of multiported or gridiron auxiliary or cut-off valves superimposed upon said main valves, actuating fixed main and governor-controlled auxiliary eccentrics for said valves, 95 mechanism for connecting each of said valves with its eccentric comprising a rock-shaft provided with a rocker-arm, a radius-bar pivoted on the frame of the engine, a link connecting the said radius-bar with the valve-rod, and a link connecting said rocker-arm with said radius-bar, so as that the maximum rapidity of movement of the valve is reached during that portion of stroke when it is opening and closing the ports and a diminution of 105 speed is given at the other end of the movement of said valve.

2. The combination with a multiported or 110 gridiron main valve for each end of the cylinder, of multiported or gridiron auxiliary or cut-off valves superimposed upon said main valves, actuating fixed main and governor-controlled auxiliary eccentrics for said valves, 115 mechanism for connecting each of said valves with its eccentric comprising a rock-shaft provided with a rocker-arm, a radius-bar, connections between said radius-bar and the valve-rod, and a link connecting said rocker-arm and radius-bar, the said rocker-arm and radius-bar being so positioned and timed relative to each other that the travel of the rocker-arm during the first part of its stroke imparts a maximum rapidity of movement to the radius-bar, and during the completion of its stroke lessens the rapidity of such movement; 120 thereby causing a diminution of the speed of the valve at a certain predetermined period.

3. The combination with a multiported or 125 gridiron main valve for each end of the cylinder, of multiported or gridiron auxiliary or cut-off valves superimposed upon said main valves, actuating fixed main and governor-controlled auxiliary eccentrics for said valves, 130 mechanism for connecting each of said valves

with its eccentric comprising a rock-shaft, a rocker-arm carried thereby, a radius-bar pivoted to the engine-frame, a link connecting said radius-bar and the valve-rod so as to form 5 a toggle-joint, and a link connecting said rocker-arm with said toggle-joint mechanism, said rocker-arm and toggle mechanism being so positioned and timed relative to each other that the maximum rapidity of movement 10 is imparted the toggle mechanism by the rocker-arm during the first part of the stroke of said rocker-arm, the rapidity of such movement being lessened during the last part of the stroke of said rocker-arm, during which 15 latter movement the said toggle-joint is forced past its center, whereby a dwell or diminution of speed is given to the valve at the end of its stroke.

4. The combination with a multiported or 20 gridiron main valve for each end of the cylinder, of multiported or gridiron auxiliary or cut-off valves superimposed upon said main valves, actuating fixed main and governor-controlled auxiliary eccentrics for said valves, 25 mechanism for connecting each of said valves with its eccentric comprising a rock-shaft hav-

ing a rocker-arm secured thereto, a radius-bar, a link connecting said radius-bar with the valve-rod of the main valve and forming with said radius-bar a toggle-joint mechanism, 30 a link connecting the rocker-arm on said rock-shaft with said toggle mechanism, said rocker-arm being so timed and positioned relative to the said toggle mechanism as that said main valve is given its maximum rapidity of movement during the first part of the stroke of said rocker-arm and a dwell or diminution of speed during the latter part of the rocker-arm stroke; a second rock-shaft provided with a rocker-arm, a bell-crank lever connected with said auxiliary valve and a link connecting the last-mentioned rocker-arm with said bell-crank lever, said second rock-shaft being 35 so timed and positioned as to give similar diminution of speed at end of stroke to said auxiliary valve as in case of the said main valve.
